UNITED STATES PATENT OFFICE.

ARTHUR R. WARREN, OF OAK PARK, ILLINOIS, ASSIGNOR TO UNIVERSAL PRINTING APPLIANCES COMPANY, OF CHICAGO, ILLINOIS, A CORPORATION OF ILLINOIS.

ELECTROTYPE FORM AND PLATE.

1,147,130.

Specification of Letters Patent. Patented July 20, 1915.

Application filed March 21, 1913. Serial No. 755,870.

To all whom it may concern:

Be it known that I, ARTHUR R. WARREN, a citizen of the United States, and a resident of the town of Oak Park, in the county of Cook and State of Illinois, have invented certain new and useful Improvements in Electrotype Forms and Plates; and I do hereby declare that the following is a full, clear, and exact description of the same, reference being had to the accompanying drawings, and to the numbers of reference marked thereon, which form a part of this specification.

Heretofore the alining of printing plates in a printing form to secure the proper register thereof as in color process work, has necessitated a number of trial impressions being made, and a number of adjustments are usually necessary before the plates are secured in proper register. Such trial adjustments are necessary for the reason that the electrotype or printing plate is usually merely clamped on each of its four sides by means of adjustable clamps, which allow the plates to be properly manipulated into a registering position, but do not serve to aid the operator in rapidly effecting such adjustment.

This invention relates to a form for electrotype whereby an accurate centering device is formed as an integral portion of the printing plate, and is thus readily adaptable to use with the quick adjusting, centering clamping devices forming the subject matter of the co-pending application of myself and Anthony F. Bals, for "printer's catch or registering means," filed Mar. 21, 1913, Serial No. 755,876.

It is an object of this invention to provide a plate form having suitably shaped blocks therein to afford coöperative means on the plates formed therefrom for quickly centering the same on a printing base equipped with centering clamps.

It is also an object of this invention to form an electrotype or other printing plate with integral means for coöperating with a centering device in a printing form.

It is also an object of this invention to afford a printing plate having an accurately formed recess therein adapted to co-act with a complementally shaped centering device

on the printing base to secure accurate adjustment of said printing plate thereon.

It is also an object of this invention to provide an electrotype form whereby suitable centering elements may be formed upon the electrotype at practically any convenient points thereon.

It is a further object of this invention to provide mold blocks in the plate form from which the wax mold is taken to afford a centering recess in the plate formed from said mold.

It is finally an object of this invention to construct a simple, compact and durable device whereby the formed plates may be made as usual without necessitating any changes in the process of formation thereof.

The invention (in a preferred form) is hereinafter described and more fully pointed out and defined in the appended claims.

In the drawings: Figure 1 is a top plan view of a type form equipped with a device embodying the principles of my invention. Fig. 2 is a front elevation of one of the type form sections embodying my invention. Fig. 3 is a section on line 3—3 of Fig. 2. Fig. 4 is a fragmentary plan view of one end of the formed electrotype showing the same provided with centering means. Fig. 5 is a top plan view of the electrotype plate mounted on the printing base, showing the operation of the centering elements. Fig. 6 is a partial longitudinal transverse central section taken through the electrotype plate. Fig. 7 is a top plan view of one of the blocks of the printing base, provided with an adjustable centering and clamping means.

As shown in the drawings: 1, indicates the outside rack or frame of a printing form, with the type 2, set up therein and maintained in the usual proper spaced relation by means of the sectional blocks 3, which are inclosed longitudinally and transversely at the sides and ends of the rack by means of the bars 4. The assembled sections comprising the form are maintained in tight relation with one another and within the rack 1, by means of the usual quoins 5. Adjacent the transverse end bars 4, of the printing form are the recessed sections 6, locked up on either side thereof by means of the sections 7. As shown in Figs. 1, 2,

and 3, said section 6, is provided in this case with a V shaped recess 8, in the upper inclined surface 9, thereof, which, when the electrotype plate 10, is formed, will exist 5 as the similarly shaped notch 11.

Fig. 7 shows one of the blocks 12, provided with the clamping member 13, which has on the clamping face thereof the integral projecting V shaped centering element 14, said block, as is usual, forming a detachable portion of the printing base 15.

The operation is as follows: In the usual process of making electrotypes, the form, as shown in Fig. 1, is set up, and a wax impression under pressure made thereof. The wax impression is then coated with plumbago, and submerged in the electrolytic solution of copper sulfate, together with a copper plate. The plumbago coated surface 20 of the wax mold is connected to the positive terminal of a source of E. M. F. and the negative terminal thereof is connected to the aforesaid copper plate submerged in the solution. A thin coating of copper is there- 25 by electrolytically deposited upon the plumbago coated surface of the wax mold, and, when the same is of sufficient thickness to permit handling, it is backed up with molten lead or type metal to approximately a thick- 30 ness of one sixth of an inch, and the printing plate is complete. The back surface and edges of the plate, as well as the V shaped notches, which were integrally cast therein, are then accurately machined and surfaced. 35 When the electrotype is used for printing it is placed upon the printing base 15, and suitably secured thereon at each of its sides by means of the adjustable clamping blocks 12 and 16, of which the blocks 12, are pro- 40 vided with the clamping members 13, hav- 45 ing the complementally shaped projecting portions 14, adapted to engage in the notches 11 in the electroplate to center the same. The usual wooden backing member 50 to which the electrotype is secured is dis- pensed with in this manner of handling the electrotype for printing purposes. Thus it is readily seen that, for instance in three color work, the electrotype plates having 55 been provided with similarly disposed V notches in the ends thereof, when said plates are mounted upon the printing base 15, at

the proper time for the application of the respective color thereof, each of said plates is brought into proper register, so that the 55 impressions will coincide.

Of course, I am aware that the particular shape of the recess in the electrotype and the engaging member of the clamping block, may be of any desired configuration, and 60 may be disposed at practically any point along the edge of the printing plate. I am further aware that details of construction may be varied to a wide range without departing from the principles of my invention, and I therefore do not purpose limiting the patent granted otherwise than necessitated by the prior art.

I claim as my invention:

1. In a device of the class described the 70 combination with printers' furniture, of V-shaped centering forming members associated therewith for a pattern mold forming a printing plate with centering notches adapted to be engaged by the centering ele- 75 ment of a printing plate.

2. In a device of the class described a printing form and recessed sections therein adapted to form centering notches in the face of a printing plate formed therefrom. 80

3. In a device of the class described the combination with printers' furniture of recessed V-shaped sections adapted to form integral centering devices on the edge of a printing plate when the same is formed. 85

4. In a device of the class described a printing form, a section insertable therein and having a V-shaped recess therein providing the printing plate formed from said form with a similarly shaped and disposed 90 recess for centering when said plate is used for printing.

5. In a device of the class described a recessed member insertable in the edge of a form adapted to provide a plate formed 95 therefrom with centering means on its edges.

In testimony whereof I have hereunto subscribed by name in the presence of two subscribing witnesses.

ARTHUR R. WARREN.
